(57) **CLAIM**

The ornamental design for a pair of baseball umpire/catcher
thigh protectors, as shown and described.

DESCRIPTION

The pair of baseball umpire/catcher thigh protector would
fulfill the need for providing the user with a protective
barrier between the thigh and the baseball which would
avoid considerable amounts of pain and contusion when the
baseball hits the thigh.

FIG. 1 is a front elevation of the right thigh protector of the
pair of baseball umpire/catcher thigh protectors, showing
my new design;

FIG. 2 is a rear view of FIG. 1;

FIG. 3 is a side elevation of FIG. 1;

FIG. 4 is a side elevation showing the side opposite of FIG.
3;

FIG. 5 is a top plan view; and,

FIG. 6 is a bottom plan view.

The left thigh protector of the pair of baseball umpire/
catcher thigh protectors is a mirror image of the thigh
protector shown in FIGS. 1 through 6.
